UNITED STATES PATENT OFFICE.

WILLIS K. HODGMAN, OF TAUNTON, MASSACHUSETTS, ASSIGNOR TO MIEHLE PRINTING PRESS & MANUFACTURING COMPANY, OF CHICAGO, ILLINOIS, A CORPORATION OF ILLINOIS.

PLANOGRAPHIC PRINTING-PRESS.

1,348,006.

Specification of Letters Patent.

Patented July 27, 1920.

Application filed October 20, 1915. Serial No. 56,838.

To all whom it may concern:

Be it known that I, WILLIS K. HODGMAN, a citizen of the United States, residing at Taunton, in the county of Bristol and State 5 of Massachusetts, have invented certain new and useful Improvements in Planographic Printing-Presses, of which the following is a specification.

My invention relates to improvements in 10 planographic printing presses and is applicable to both the direct type and the off-set type of press. In the direct type of press the printing plate prints direct upon the material to be printed and in the offset type 15 the printing plate prints upon a rubber blanket, or the like, which in turn transfers or offsets the design upon the material to be printed. Both methods of printing are well known and need no further description except to call attention to the fact that in both 20 types of press the printing members (plate cylinder or flat bed, offset cylinder and impression cylinder) are all timed relative to each other and each equipped with an impression 25 surface of sufficient area to receive the whole of the largest design the press is intended to print.

The objects of my invention are, first, to provide, in place of the usual impression 30 cylinder, an impression member in the form of a roll, of comparatively small diameter and having a true and unbroken periphery which will therefore, give the same printing pressure at any part of its periphery 35 and need not be timed relative to its co-acting member; second, to provide suitable means to rotate the impression roll at a surface velocity best suited to the work being done and which can be readily adjusted 40 to give the desired surface velocity whether or not it be exactly the same as the surface velocity of the impression roll's co-acting member or a trifle faster or slower; third, to provide, in printing presses wherein 45 sheets are fed to the grippers of a cylinder which carries a freshly inked design, suitable means to prevent the sheets from contacting with the freshly inked design before the proper time of impression; and, fourth, 50 to provide suitable means to feed sheets in accurate register between two printing members neither of which is equipped with grippers or wherein, when grippers are used, the grippers are not closed upon the

sheet until after its leading edge has passed 55 between the two printing members.

In order that the invention may be readily understood by those skilled in the art, preferred and modified embodiments of the same are set forth in the accompanying 60 drawings and in the following detailed description predicated thereon. Obviously the invention may be embodied in other and varied constructional forms, wherefore it is to be understood that the drawing and description are to be taken in an illustrative 65 and not in an unnecessarily limiting sense. In the drawings—

Figure 1 shows a central longitudinal section of a rotary planographic offset press 70 embodying my invention;

Fig. 2 is an enlarged side elevation of the same, illustrating the mechanism for tripping or separating the cylinders;

Fig. 3 is an enlarged broken view of the 75 same, partly in end elevation and partly in cross section;

Fig. 4 is a fragmentary sectional view 80 illustrating another and mechanical means for controlling the contact of the sheet with the design to be printed;

Fig. 5 is a diagrammatic view illustrating in outline a two-color rotary offset press embodying my invention;

Figs. 6 and 7 are fragmentary views re- 85 spectively in vertical section and front elevation of a rotary planographic press equipped with mechanism for attaining the fourth object of my invention;

Fig. 8 is a diagrammatic sectional view 90 showing a single color rotary planographic printing press of the direct type equipped with my invention; and

Fig. 9 shows a modified arrangement of 95 the gripper mechanism.

From an inspection of the drawing and having particular reference to Figs. 1 to 3, it will be seen that, the moving parts are mounted in suitable framework consisting of the side frames 1 and 2, and the cross-stay 3, while the plate cylinder 4 is journaled in stationary bearings in the side frames and is equipped with a printing plate 5 in the usual manner. Above the plate cylinder 4, (Fig. 1) the usual ink fountain, ink drum 100 and ink rollers are shown, and at its right are the usual water fountain and water rollers, all of which operate in the usual

manner to supply ink and water to the printing plate 5 and need no further description. At 46 is indicated the feed board and at the opposite end of the press is the delivery board 7 which may be arranged, in any well known manner to be gradually lowered, as the printed sheets accumulate upon it.

The offset cylinder 8 is journaled in movable eccentric bearings 9 mounted in the side frames and is equipped with a rubber blanket 10 in the usual manner. The feeding cylinder 11 is journaled in stationary bearings in the side frames. The delivery cylinder 12 is journaled in rectangular boxes 13 which are slidably mounted in the side frames, and the sheet delivery reels 14 and 15 are journaled in stationary bearings in the side frames.

The cylinders 4, 8, 11, 12 and the delivery reel 15 are respectively equipped with co-acting gears 16, 17, 18, 19 and 20 (gear 20 shown in dotted lines only) and are rotated at continuous and uniform speed, in the direction indicated by arrows, by the driving pinion 21 which is fixed on the short shaft 22, journaled in the side frame 2, and having fixed on the outer end the usual driving pulley 23. The delivery reel 14 is rotated from the reel 15 by the usual sprocket 24 chains, shown in dotted lines only, which carry the usual gripper rods, grippers and gripper rests, indicated at 24, which operate in the usual well known manner to receive the printed sheets from the delivery cylinder 12 and deposit them, printed side up, upon the delivery board 7.

The two side rods 25 are fitted to slide in vertical guide ways, in the side frames 1 and 2, and have a slight up and down range of position which is controlled by the eccentric rock shaft 26, journaled in the side frames, and which is used, at the will of the operator, through mechanism to be described, to move and position the side rods against the pressure of the springs 27, which are always striving to force them up.

The mechanism for operating the side rods 25 consists, in addition to the eccentric rock shaft 26, of the two treadle levers 28, set-screwed to it; the two slide-blocks 29, which partly surround the eccentric ends of the rock shaft, just inside the levers 28, and slide when the shaft 26 is rocked, on the two gibbs 30 which are adjusted, by the two set-screws 31, tapped through the lower ends of the side rods, to regulate the vertical positions of the side rods and, through them, the position of the impression roll 32, which is journaled in their upper ends.

The compression springs 27 are positioned on the guide rods 33 which are firmly held, by set screws, at their lower ends, in the projecting lugs 34 of the side frames. The upper ends of the guide rods 33 fit loosely in the lugs 35 on the side rods 25 and the

springs 27, thus confined between the lugs 34 and 35, exert sufficient pressure upward to more than counterbalance the weight of the side rods 25 and impression roll 32 and hold the latter firmly and with printing pressure against the offset cylinder when the press is printing. The flanged pulley 36 which is secured to one end of the feeding cylinder 11, by two bolts, (Fig. 3) drives the impression roll by means of its flanged pulley 37, shown in dotted lines only, and the connecting belt 38, also shown in dotted lines only.

The pulleys 36 and 37 and the belt 38 furnish one simple, effective and very inexpensive means for accomplishing the second object of my invention, for it is obvious that a few pulleys 37, of slightly different diameters, could be kept on hand and the right one used to exactly meet the requirements caused by different thicknesses of stock being printed. The preferable arrangement is a slack belt over pulleys 36 and 37 of normal diameters, which drives the impression roll 32 at substantially correct velocity at all times but allows it to be controlled during printing periods by its peripheral contact with the material being printed upon the offset cylinder 8.

It will now be readily understood that I have accomplished the first object of my invention by providing, in place of the usual cumbersome, expensive and necessarily timed impression cylinder, the comparatively small and inexpensive hollow metal impression roll, which does not have to be timed because its periphery is unbroken and can be accurately finished to be perfectly smooth, true and of the same diameter at every point. In other words, in this new and novel impression roll is found a most simple and satisfactory instrumentality for pressing the material to be printed against the design upon the offset cylinder because it does its work without any undue drag or friction upon the surface of the said material, which is absolutely essential when fine and continuous results are demanded.

When the operator desires to trip, or separate the impression roll from the offset cylinder, he depresses, by using the one nearest at hand, the treadle levers 28 to the dotted position (Fig. 2) which, through the mechanism previously described, compresses the springs 27 and moves the impression roll 32 away from the offset cylinder 8, and down (in practice about $\frac{1}{8}$ ") from its printing position.

For tripping the offset cylinder 8 relative to the plate cylinder 4 I have shown a common form of mechanism consisting of the two eccentric bearings 9, two connecting rods 39, two levers 40, which latter are fixed on the ends of the rock shaft 41, which has bearings in the side frames 1 and 2; and

it will be understood that by means of the usual cam (not shown) and the usual connections (not shown) between said cam, rock shaft 41 and the levers 28, the offset cylinder 8 is, after the levers 28 are depressed, caused to be properly tripped and moved (in practice about $\frac{1}{16}$ " away from the plate cylinder 4. This tripping mechanism for the offset cylinder 8 being well known and forming no part of my invention, needs no further description other than to mention that the eccentric bearings 9 are so positioned as to move the cylinder, when tripped in a path that does not perceptibly alter its distance from the feeding cylinder 11 and to point out the reason why the offset cylinder 8 does not conflict, when being tripped, with the delivery cylinder 12 which is located directly in its path. The following description will make the reason plain—the offset cylinder 8 and the delivery cylinder 12 are both equipped with co-acting distance bearers 42 which, together with the spring-pressed rectangular slide boxes 13, (plainly shown in Fig. 2) act to move the delivery cylinder 12 in unison with the offset cylinder 8 and maintain their center distance always the same. The paths of the guideways in the side frames for the boxes 13 are made to guide the movement of the delivery cylinder 12 without perceptibly altering the distance between it and the delivery reel 15.

The feeding cylinder 11, offset cylinder 8 and delivery cylinder 12, each carry the usual gripper rod 43, grippers 44 and gripper rests 45 which together with the usual operating mechanism, not shown, act respectively in the usual way to direct and carry the sheets through the press from the feed board 46 to the offset cylinder 8, thence to the delivery cylinder 12 and thence to the chain delivery gripping devices 24 previously described and need no further description other than to mention that the grippers of the offset cylinder 8 when closed are, as is usual in many planographic printing presses, slightly within its periphery so as not to strike the co-operating printing member which, in this case, is the impression roll 32.

The feeding cylinder 11 is hollow and substantially air tight excepting for the small holes 47 which are drilled through that part 55 of its shell which contacts with the sheets when they are passing from the feed board 46 into the press. The hole 48, (Fig. 3) drilled through one journal of the feeding cylinder 11, and counter-bored to receive the 60 shouldered end of the stationary pipe 49, which latter is connected to an exhaust fan, not shown, connects the interior of the cylinder 11 with the said exhaust fan. It will now be understood that a partial vacuum 65 can be created, in the feeding cylinder 11,

and readily regulated to suit the different thicknesses of the materials to be printed by a valve, not shown, in the exhaust pipe 48 and that by means of the small holes 47, the sheets, as they pass into the press, will 70 be hugged against the periphery of the feeding cylinder, which is of less than normal diameter to make room, and thus prevented from contacting with the inked design upon the offset cylinder 8, until they 75 are correctly pressed against it by the impression roll 32.

I have now described and illustrated one way of attaining the third object of my invention but will, before passing, describe 80 and illustrate another way of accomplishing the same object and by using mechanical means only, reference being had to Fig. 4. The exhaust fan and all the other parts and construction necessary to the pneumatic arrangement are discarded and the shape of the body part of the feeding cylinder 11 is changed to the shape plainly shown in the drawing. The common front guide mechanism, consisting of the front guides 85 50, the shaft 51 and other regular parts, not shown, is arranged to operate in the usual manner. The under-guides 52 and the over-guides 53 are respectively set-screwed to their rock shafts 54 and 55, which are journaled in the side frames, and connected together by means of the levers 56 and 57, also set-screwed to the said rock shafts, and the connecting rod 58. Near one end of the rock shaft 54 is set-screwed the lever 59, 100 which carries on a stud at its free end the roller 60 which travels in the cam groove 61 in one end of the feeding cylinder 11.

It will now be readily understood that the front-guides 50, under guides 52 and over-guides 53 will be held in the positions indicated by the dotted lines, during the time the sheets are being placed in position to enter the press, and that shortly after the front-guides lift and the grippers 105 on the feeding cylinder seize the sheets the under-guides and over-guides will gradually take the positions indicated by the solid lines and thus guide the sheets, away from contact with the inked design upon 110 the offset cylinder and to the impression point between the offset cylinder and the impression roll substantially along the path indicated by the dotted line 62.

In Fig. 5 is shown in outline a two color 120 rotary offset press embodying my invention and to which it lends itself very readily. All the parts described and shown in Figs. 1 to 4 are, or can be used substantially without change, excepting that the delivery cylinder 12 and its co-acting delivery parts are separated from the balance of the press and moved forward sufficiently to make room for the second color device which consists of the transfer cylinder 63, plate cylinder 125 130

4^a, offset cylinder 8^a, impression roll 32^a and their operating parts. On account of the additional work of driving the second color device I have journaled the transfer cylinder 63 in movable eccentric bearings 9^a mounted in the side frames, and connected to the eccentric bearings 9 by connecting rods 64, so that the transfer cylinder 63 is moved in unison with the offset cylinder 8 and positively positioned.

It will now be readily understood that the several sets of grippers 44, operating in the usual way, will direct and carry the sheets through the press from the feed board 46 to the offset cylinder 8, thence to the transfer cylinder 63, thence to the offset cylinder 8^a, thence to the delivery cylinder 12, and thence to the chain delivery gripping devices 24 which deposit the sheets printed side up upon the delivery board 7.

I have shown and described my invention as applied to a two color rotary press but it is obvious that the principle of construction comprehends a rotary multi-color press of any desired number of colors and simply calls for the additional overall length necessary for each color device.

In Figs. 6 and 7 is shown mechanism applied to a rotary planographic offset press, 30 for attaining the fourth object of my invention.

The feeding cylinder which is made up of a suitable number of reels 11^a is one-half the diameter of the offset cylinder 8 and is driven from it by gears, not shown, to make two revolutions while the cylinder 8 makes one. The reels 11^a are set-screwed to the shaft 65 journaled in the side frames and are equipped with grippers 44 closing on 35 the gripper rests 45^a which are bolted to one side of the reels 11^a as plainly shown in Fig. 6. The grippers 44 act in the usual manner to take the sheets from the feed board 46 but after carrying them a short 40 distance, in practice about $\frac{3}{4}$ inch, they release their hold and then the feeding of the sheets is controlled by the friction wheels 66, until they are impinged between the offset cylinder 8 and the impression roll 32, 45 as will be explained.

The friction wheels 66, are mounted to rotate on studs in the free ends of the levers 67, which latter are fulcrumed on the stationary shaft 68 and between the hubs of 50 the fingers 69 which are set-screwed to the shaft 68. Located between the levers 67 and the fingers 69 are compression springs 70 which act to force the friction wheels against the unbroken peripheries of the 55 feeding reels 11^a which are all of the same diameter.

The under guides 52^a set screwed to the stationary shaft 54^a and the over-guides 53^a, set screwed to the stationary shaft 55^a, act 60 to guide the sheets to the printing point be-

tween the offset cylinder 8 and the impression roll 32. The sheet guides 71, setscrewed to the shaft 72, which is mounted in movable brackets, not shown, to move in unison with the offset cylinder 8 and always maintain the same position relative to it. The sheet guides 71, can therefore be adjusted to just clear the surface of the sheets when on the offset cylinder and act to prevent them from dropping away from the offset cylinder and keep them in position to be taken by the grippers 44 of the delivery cylinder 12 as previously described.

It not being necessary to have grippers on the offset cylinder the rests 45^a are fitted almost even with its periphery and serve to prevent the gripper edges of the sheets from turning in and to keep them straight and in position to be taken by the grippers of the delivery cylinder.

Grippers can be used on the offset cylinder 8 and when used are arranged to close upon the sheets after they have passed between the offset cylinder and the impression roll and therefore no change is required in the height of the rests 45^a because the grippers are always open when passing the impression roll 32. The bite of the friction wheels 66 is located a short distance (in practice about $\frac{1}{4}$ inch) ahead of the gripper edges of the sheets, when they are against the front guides 50 and the grippers 44 of the feeding reels 11^a are arranged to open and release the sheets a short distance (in practice about $\frac{1}{2}$ inch) ahead of the bite of 100 the friction wheels.

It will now be readily seen that when a sheet is fed into the press, it is taken from the feed board 46 (Fig. 6) by the grippers 44, of the feeding reels 11^a, in the usual manner, then carried by the grippers under the friction wheels 66, when it is controlled jointly by the grippers and friction wheels until the grippers open when the control is left entirely to the friction wheels which feed it, between the guides 52^a and 53^a, until it is impinged between the offset cylinder 8 and the impression roll 32. In other words, the sheet is started in register from the feed board in the usual manner and then controlled by the friction wheels pressing it against the peripheries of the reels 11^a until the printing begins.

The dotted line 62 shows a sheet that has been fed in the manner described and is about to enter between the offset cylinder and the impression roll.

In Fig. 8 is shown in outline a single color rotary planographic printing press of the direct type. In this type of press it is necessary to equip the impression surface of the impression member with a yielding surface of rubber or the like and in the drawing I have illustrated the impression roll 32^b as having a covering 73, of rubber finished 130

true and unbroken. Owing to the methods of rotating the impression roll, previously described, its diameter is not fixed and consequently when the surface of a roll, 5 through accident or long service, becomes slightly dented or worn it can be re-claimed by refinishing it to a smaller diameter. The impression roll can be readily removed or replaced and it is customary to keep an 10 extra one on hand, especially when covered with rubber to prevent any delay.

Referring to Fig. 8, the plate cylinder 4^b is journaled in stationary bearings in the side frame, not shown, and carries the 15 printing plate 5^a which is supplied with water and ink, in the regular manner by the usual water and ink devices, indicated by dotted rollers respectively at the left and top of the plate cylinder. The leading 20 edge of the plate 5^a is clamped to the cylinder 4^b by the sheet rests 45^b which become gripper rests also, when the plate cylinder is equipped with grippers.

In the press illustrated in this figure the 25 plate cylinder is not equipped with grippers because the method of feeding and controlling the sheets is similar to the method described and shown in Figs. 6 and 7 and which, as already understood, does not require 30 the cylinder carrying the design which contacts with the sheets to be printed to be equipped with grippers, although it can be.

The impression roll 32^b is journaled in 35 movable bearings, not shown, which are of usual construction and operation and enable it to be tripped or separated from the plate cylinder 4^b at the will of the operator and it is rotated from the feeding cylinder or 40 reels 11^b by the pulleys 36 and 37 and the belt 38, as is readily understood from previous description of similar parts.

The feeding of the sheet from the feed board 46 and the control of it is effected 45 in the way already described with reference to Figs. 6 and 7 but it will be noted that in the present application of the similar parts the underguides 52^b and over-guides 53^b are curved around the top of the feeding 50 reels 11^b and that the distance from the front guides 50 to the bite of the friction wheels 66 is increased.

It will now be readily understood that in this application of my invention to a rotary 55 planographic press of the direct type, the sheets are taken from the feed board 46 by the grippers 44, of the feeding reels 11^b in the usual manner, then carried by the grippers under the friction wheels 66, when 60 they are controlled jointly by the grippers and friction wheels until the grippers open, when they are controlled by the friction wheels 66 and the feeding reels 11^b which feed them between the guides 52^b and 53^b 65 to the printing point between the plate cyl-

inder 4^b and the impression roll 32^b, then they are guided by the sheet guides 71 until they are taken by the grippers 44 of the delivery cylinder 12 which deliver them to the chain delivery gripping devices 24 which deposit them, printed side up, upon the delivery board 7.

When the impression roll is used in an offset printing press it can be wholly of metal or it can have a yielding surface of 75 rubber or the like, but when used in a direct printing press, either planographic or typographic, it is preferably equipped with a yielding surface.

In Fig. 4 I have shown the offset cylinder 80 8 equipped with grippers 44 which latter, when closed, are slightly within the periphery of the offset cylinder to keep them from contacting with the impression roll 32. Now, as I have already mentioned, this 85 method of closing grippers within the periphery of a cylinder is common in many planographic printing presses and quite satisfactory although it slightly bends the gripper edges of the sheets. It is obvious, however, that for close register work it is best 90 that the sheets be kept as flat and smooth as possible at all times. Therefore grippers which do not tend to bend the edges of the sheets are preferable and in Fig. 9 I have 95 illustrated the preferred grippers as applied to the offset cylinder 8 of Fig. 4. The gripping ends of the gripper rests 45 are in line with the surface of the rubber blanket 10 and therefore the gripping ends of the grippers 44, when closed, project the amount of their thickness beyond the surface of the blanket.

To prevent the closed grippers 44 from striking the impression roll 32 the offset cylinder 8 is equipped with two cams 74, each 100 bolted with two bolts to the ends of the said cylinder. The cams 74 project beyond the surface of the blanket 10 a little more than the thickness of the grippers 44 and acting 105 against the periphery of the impression roll 32 compress the springs 27 (Fig. 2) sufficiently to permit the grippers to freely 110 pass the impression roll when the latter is returned by the springs 27 to printing position.

I might now describe and illustrate by drawings my impression roll and means for feeding and controlling the sheets as applied to a rotary multi-color planographic printing press of the direct type and the same as 115 applied to single and multi-color rotary typographic presses but it seems unnecessary in the light of what has gone before and of the following claims which clearly set forth the novel features and combinations which 120 I claim as my invention.

I claim:

1. In a rotary printing press, a cylinder carrying a design to be printed, an impression roll having a true and unbroken pe- 130

riphery to press the sheets to be printed against the said design, and frictional driving means providing slippage to rotate the said impression roll from a source of power other than the printing cylinder at a velocity flexibly suited to the work being done.

2. In a rotary printing press, a cylinder carrying a design to be printed, an impression roll having a true and unbroken periphery to press the sheets to be printed against the said design, and frictional driving means independent of the printing cylinder tending to rotate the said roll normally at substantially the velocity of the said cylinder but permitting slippage whereby the said roll may follow the surface velocity of the said sheets when pressing them against the said design.

3. In a rotary printing press, a cylinder carrying a design to be printed, an impression roll of materially less diameter than that of the printing cylinder and having a true and unbroken periphery to press the sheets to be printed against the design on the printing cylinder, and driving means for the impression roll, said driving means including a belt and pulleys constituting friction means to permit of the impression roll accommodating itself by slippage to the same surface speed as that of the design.

4. In a rotary printing press, a cylinder carrying a design to be printed and also provided with grippers, an impression roll free from grippers and having a true and unbroken periphery positioned beneath the said cylinder, a sheet feeding cylinder equipped with grippers positioned at one side of the impression roll, and a sheet delivering cylinder equipped with grippers positioned at the opposite side of the impression roll.

5. In a rotary printing press, a cylinder carrying a design to be printed, an impression roll having a true and unbroken periphery positioned beneath the said cylinder, a sheet feeding cylinder equipped with grippers positioned at one side of the impression roll, a sheet delivering cylinder equipped with grippers positioned at the opposite side of the impression roll, means to move the impression roll into and out of printing relation with the design carrying cylinder, and frictional driving means for the impression roll tending to rotate it at substantially the velocity of the design carrying cylinder but permitting it to follow the exact velocity of the design carrying cylinder when in printing relation with it.

6. In a rotary offset printing press, a cylinder carrying a design to be printed, an offset cylinder carrying a rubber blanket and equipped with grippers positioned beneath the design carrying cylinder, an im-

pression roll having a true and unbroken periphery positioned beneath the offset cylinder, a sheet feeding cylinder equipped with grippers, positioned at one side of the impression roll and co-acting with the offset cylinder, a sheet delivering cylinder equipped with grippers positioned at the opposite side of the impression roll and co-acting with the offset cylinder, means to move the impression roll into and out of printing relation with the offset cylinder, and a driving belt for the impression roll tending to rotate it normally at substantially the velocity of the offset cylinder but permitting it to follow the exact velocity of the offset cylinder when in printing relation with it.

7. In a rotary printing press, a cylinder equipped with grippers and carrying a design to be printed, an impression cylinder, a feeding mechanism to feed sheets into the said grippers, and means to hold the sheet away from the design cylinder until reaching the impression cylinder whereby to prevent the said sheets from contacting with the said design before reaching the said impression cylinder prior to the proper time of impression.

8. In a rotary printing press, a cylinder equipped with grippers and carrying a design to be printed, an impression cylinder, a perforated hollow feed cylinder to feed the sheets into the said grippers, and suction means to cause the sheet to hug the periphery of the feed cylinder whereby to hold the same away from contact with the design until pressed thereagainst by the impression cylinder.

9. In a rotary multi-color printing press, printing couples each consisting of a cylinder carrying a design to be printed and also provided with grippers and an impression roll free from grippers and having a true and unbroken periphery, a sheet feeding cylinder equipped with grippers to feed a sheet to the first printing couple, a cylinder equipped with grippers to transfer the sheet from the first printing couple to the next printing couple, and a cylinder equipped with grippers to take the sheet from the last printing couple and deliver it to a sheet carrying and piling mechanism.

10. In a rotary multi-color offset printing press, printing trios each consisting of a cylinder carrying a design to be printed and also provided with grippers, an offset cylinder and an impression roll free from grippers and having a true and unbroken periphery, a sheet feeding cylinder equipped with grippers to feed a sheet to the first printing trio, a cylinder equipped with grippers to transfer the sheet from the first printing trio to the next printing

trio, and a cylinder equipped with grippers to take the sheet from the last printing trio and deliver it to a sheet carrying and piling mechanism.

5 11. In a rotary printing press, a cylinder carrying grippers which when closed project beyond the periphery of the said cylinder, a co-acting cylinder, and means to move the co-acting cylinder to permit the free
10 passage of the said grippers between the

said cylinders and then return the co-acting cylinder to printing position.

In testimony whereof I have hereunto signed my name in the presence of two subscribing witnesses.

WILLIS K. HODGMAN.

Witnesses:

FRED H. NOYES,
NOBLE W. ASHLEY.
